(57) **CLAIM**

The ornamental design for a fluid pressure cylinder, as shown.

DESCRIPTION

FIG. 1 is a front, top and left side perspective view of a fluid pressure cylinder showing a first embodiment of my new design;

FIG. 2 is a rear, bottom and right side perspective view thereof;

FIG. 3 is a front view thereof;

FIG. 4 is a rear view thereof;

FIG. 5 is a top plan view thereof;

FIG. 6 is a bottom plan view thereof;

FIG. 7 is a left side view thereof;

FIG. 8 is a right side view thereof;

FIG. 9 is a front, top and left side perspective view of a fluid pressure cylinder showing a second embodiment of my new design;

FIG. 10 is a rear, bottom and right side perspective view thereof;

FIG. 11 is a front view thereof;

FIG. 12 is a rear view thereof;

FIG. 13 is a top plan view thereof;

FIG. 14 is a bottom plan view thereof;

FIG. 15 is a left side view thereof;

FIG. 16 is a right side view thereof;

FIG. 17 is a front, top and left side perspective view of a fluid pressure cylinder showing a third embodiment of my new design;

FIG. 18 is a rear, bottom and right side perspective view thereof;

FIG. 19 is a front view thereof;

FIG. 20 is a rear view thereof;

FIG. 21 is a top plan view thereof;

FIG. 22 is a bottom plan view thereof;

FIG. 23 is a left side view thereof;

FIG. 24 is a right side view thereof;

FIG. 25 is a front, top and left side perspective view of a fluid pressure cylinder showing a fourth embodiment of my new design;

FIG. 26 is a rear, bottom and right side perspective view thereof;

FIG. 27 is a front view thereof;

FIG. 28 is a rear view thereof;

FIG. 29 is a top plan view thereof;

(Continued)

FIG. 30 is a bottom plan view thereof;
 FIG. 31 is a left side view thereof;
 FIG. 32 is a right side view thereof;
 FIG. 33 is a front, top and left side perspective view of a fluid pressure cylinder showing a fifth embodiment of my new design;
 FIG. 34 is a rear, bottom and right side perspective view thereof;
 FIG. 35 is a front view thereof;
 FIG. 36 is a rear view thereof;
 FIG. 37 is a top plan view thereof;
 FIG. 38 is a bottom plan view thereof;
 FIG. 39 is a left side view thereof;
 FIG. 40 is a right side view thereof;
 FIG. 41 is a front, top and left side perspective view of a fluid pressure cylinder showing a sixth embodiment of my new design;
 FIG. 42 is a rear, bottom and right side perspective view thereof;
 FIG. 43 is a front view thereof;
 FIG. 44 is a rear view thereof;
 FIG. 45 is a top plan view thereof;
 FIG. 46 is a bottom plan view thereof;
 FIG. 47 is a left side view thereof;
 FIG. 48 is a right side view thereof;
 FIG. 49 is a front, top and left side perspective view of a fluid pressure cylinder showing a seventh embodiment of my new design;
 FIG. 50 is a rear, bottom and right side perspective view thereof;
 FIG. 51 is a front view thereof;
 FIG. 52 is a rear view thereof;
 FIG. 53 is a top plan view thereof;
 FIG. 54 is a bottom plan view thereof;
 FIG. 55 is a left side view thereof;
 FIG. 56 is a right side view thereof;
 FIG. 57 is a front, top and left side perspective view of a fluid pressure cylinder showing an eighth embodiment of my new design;
 FIG. 58 is a rear, bottom and right side perspective view thereof;
 FIG. 59 is a front view thereof;
 FIG. 60 is a rear view thereof;
 FIG. 61 is a top plan view thereof;

FIG. 62 is a bottom plan view thereof;
 FIG. 63 is a left side view thereof;
 FIG. 64 is a right side view thereof;
 FIG. 65 is a front, top and left side perspective view of a fluid pressure cylinder showing a ninth embodiment of my new design;
 FIG. 66 is a rear, bottom and right side perspective view thereof;
 FIG. 67 is a front view thereof;
 FIG. 68 is a rear view thereof;
 FIG. 69 is a top plan view thereof;
 FIG. 70 is a bottom plan view thereof;
 FIG. 71 is a left side view thereof; and,
 FIG. 72 is a right side view thereof.
